DOOR CLOSER

Henry S. Diebel, Downey, Calif., assignor to
G. G. Bakewell, Pasadena, Calif.

Application August 19, 1946, Serial No. 691,558

3 Claims. (Cl. 16—50)

1

This invention relates to a spring closer hinge for a door.

Reference is made to my co-pending application Serial No. 691,559 filed August 19, 1946, which relates to the hydraulic hinge shown in this application.

One object of my invention is to provide an actuating hinge unit to mount a door. Another object is to provide a door closer hinge adapted to carry the weight of a door. A further object is to provide means in a door closing hinge for adjusting the relative elevations of the leaves after the door is hingedly mounted on the door frame in order to shift the load of the door weight to the closer hinge. These and other objects are attained by my invention which will be understood from the following description, reference being made to the accompanying drawings in which:

Fig. 1 is a front elevational view showing a pair of hinges mounting a door on a doorframe;

Fig. 2 is a cross-sectional view taken on the line 2—2 of Fig. 1;

Fig. 3 is a cross-sectional view taken on the line 3—3 of Fig. 2;

Fig. 4 is a cross-sectional view taken on the line 4—4 of Fig. 2;

Fig. 5 is a cross-sectional view taken on the line 5—5 of Fig. 2;

Fig. 6 is a cross-sectional view taken on the line 6—6 of Fig. 2;

Fig. 7 is a cross-sectional view taken on the line 7—7 of Fig. 2;

Fig. 8 is a cross-sectional view taken on the line 8—8 of Fig. 2;

Fig. 9 is a cross-sectional view taken on the line 9—9 of Fig. 2;

Fig. 10 is a cross-sectional view taken on the line 10—10 of Fig. 2;

Fig. 11 is a cross-sectional view similar to Fig. 9, but showing the position of the piston in the retarding portion of the cycle the dowel pin being omitted in this view;

Fig. 12 is a cross-sectional view taken on the line 12—12 of Fig. 8.

In general, my invention includes a pair of hinges adapted to hingedly mount a door on a doorframe, one of the hinges having an hydraulic checking mechanism for controlling the angular movement of the door and the other hinge having a coil spring actuator mechanism which is adapted to store up energy from the hand operation of opening the door and then to release the energy to actuate the door in the closing direction. The actuator hinge is provided with a thrust bearing and elevating means by which,

2

after installation of the hinges on the door and doorframe, the relative elevations of the two leaves may be adjusted so that the weight of the door is carried on the thrust bearing and the hydraulic checking hinge is substantially free from any downward thrust due to the weight of the door.

Referring to the drawings, the closer or actuator hinge 20 and the hydraulic checking hinge 21 are mounted on the door 22 hingedly supporting it on the doorframe 23. The closer hinge 20 consists of a hollow cylindrical casing 24, having a cavity 25 and an attached or integral leaf 26 which is provided with screw holes 27 for attachment of the hinge leaf. A hinge pin 28 is mounted in a thrust bearing 29 at the bottom of the cavity 25 and in a sleeve bearing 30 near the upper end of the casing, the bearing being held in place by the bushing 31 which is screw threaded into the upper end of the cavity of the casing 24. The bushing 31 is provided with radial holes 32 adapted to be engaged by a spanner wrench or the like for step-by-step rotation of the bushing, a stop pin 33 being provided for insertion in one of the holes to prevent the unwinding of the coil spring 34, which is disposed around the hinge pin 28 within the cavity 25. The coil spring 34 is anchored at the lower end 35 in the radial hole 36 in the hinge pin near the bottom of the cavity 25 and it is also anchored at the upper end 37 in the hole 38 in the bushing 31. When the spring is wound up, the stop pin 33 presses against the leaf 26 to prevent the unwinding of the spring. The slot in the upper end of the casing 24 opposite the leaf 26 adjacent the radial holes 32 may be covered by a covering snap ring 40. The lower end of the hinge pin 28 is tapered to fit in the inner ring 41 of the thrust ballbearing 29, the outer retainer ring 42 of the ballbearing being seated near the bottom of the cavity 25 of the casing 24.

The upper end of the hinge pin 28 above the bushing 31 is non-circular, preferably hexagonal, in cross section. The other leaf 43 of the closer hinge 20 is provided with a cylindrical hub 44 in the axis of which is a non-circular or hexagonal hole 45 adapted to slidably fit over the non-circular or hexagonal upper end of the hinge pin 28. The upper part of the hole 45 is cylindrical and threaded to engage the threaded lift screw 47, this lift screw being provided with a tool engaging cavity 48 which permits the screw to be turned by a suitable tool. A closing cap 49 is adapted to slip over the hub 44, with a vertical slot fitting over the leaf 43. The leaf

43 is also provided with screw holes 27 for attaching the hinge to the edge of the door 22.

The hydraulic checking hinge 21 consists of a casing 55 having a cylindrical cavity and an attached or integral leaf 57 with screw holes 27 for attaching the leaf to the door frame 23. A hinge pin 58 is mounted in the cavity 56, the hinge pin being pivoted in the bearing 59 in the bottom of the casing 55. A sleeve bearing 60 is provided at the upper end of the cavity 56 being held in place by the closure bushing 61 which is screw threaded into the top of the cavity 56. A reservoir cup 62 is provided in the upper end of the cavity 56 below the closure bushing 61, locking rings 63 and 64 being provided to hold the reservoir cup in position. Below the reservoir cup 62 is provided a segmental partition member or dam 65 whose radial ends form the end walls of a working chamber 66 for the hydraulic piston 67 which is attached to the hinge pin 58 within the working chamber. The segmental partition member or dam 65 is preferably made integrally with the casing 55. The reservoir cup 62 is positioned radially by means of the dowel pin 68 in corresponding holes in the dam 65 and the reservoir cup 62. The flow of hydraulic liquid from one side of the piston 67 to the other, during the movement of the piston in the working chamber is controlled by variable constructed conduits to give the selected effects upon the door opening and closing. The upper end of the hinge pin 58 is provided with an axial hole 69 in which the metering pin 70 slides, the upper portion of the hole 69 being threaded to permit adjustment of the position of the metering pin through the knurled end 71 extending beyond the upper end of the hinge pin. The metering pin near its lower end is provided with a tapered portion where it intersects a hole 72 through the hinge pin 58, leading from one side of the piston 67 to the other. By adjusting the position of the metering pin relative to the hole 72 the hydraulic friction of the hydraulic liquid passing through this hole may be regulated. Also a oneway conduit 73 is provided through the hinge pin 58 within the working chamber 66, this one way conduit having a seated ball 74 and retainer 75 therefor which permits the liquid to flow freely from one side of the piston to the other, but shuts off the flow when the movement is in the opposite direction.

The reservoir cup 62 is hydraulically connected to the working chamber by two checked-valved orifices 76 which permit the hydraulic fluid to flow from the reservoir into the working chamber on either side of the piston but prevent it from flowing in the opposite direction. The hydraulic liquid in the reservoir is nonpressured and in the event that any hydraulic liquid leaks out of the working chamber, it is replenished from the reservoir when a reduced pressure results in the working chamber on one side of the piston from the rotary movement of the piston. The lower surface of the reservoir cup serves as the upper wall of the working chamber 66. This surface is provided with grooves of varying sizes which effect the hydraulic friction at different angular positions of the piston. As shown, the groove 78 starting from the open position of the hinge is large enough in cross-sectional area so that substantially no hydraulic friction is introduced in the initial movement of the hydraulic piston 67 from the open position of the hinge. As the piston approaches the closed hinge position, a

tapered constricted groove 79 is provided for a few degrees of rotation to retard the movement, and as the hinge (and the door) approaches complete closing, the unrestricted groove 80 is provided so that the energy from the closer hinge 20 will cause the attached door to close completely into the latch. In the opposite direction of movement of the piston, the hydraulic liquid flows freely through the one way conduit 73 so that the grooves in the reservoir bottom do not affect the hydraulic friction in the opening direction of movement.

The other leaf 85 which is usually attached to the edge of the door by screw holes 27 is provided with a split clamp member 86 having an axial hole 87 adapted to engage the upper end portion 88 of the hinge pin 58. Clamp screws 89 are provided in the clamp member 86 to hold it non-rotatably on the hinge pin 58 in the upper portion 88. A closing cap 49 may be provided to cover the knurled adjusting end 71 of the metering pin.

The use of the closer hinge carrying the weight of the door in combination with another hinging unit coacting to hold the door in hinged relation to the door-opening but carrying none of the weight of the door, allows the precision hydraulic mechanism to function for long periods of time, without the requirement of servicing or adjustment. The door may be mounted in the usual way by screws fastening the leaves to the edge of the door and the doorframe and then the lift screw 47 adjusted so that the weight of the door is shifted to the closer hinge which is particularly adapted to carry a load. The hydraulic hinge, with its precision construction is protected from wear in the hydraulic surfaces by shifting the load to the closer hinge. Since a door is always mounted with a minimum of two hinges, it is possible to provide the control hinge and the closer hinge of similar outside ornamental design and of inconspicuous proportions so that door control in homes and other places where inconspicuous accessories are desired, is now possible by use of this invention.

I claim:

1. A load-bearing closer hinge comprising a hollow cylindrical casing, a casing leaf attached by an edge to said hollow casing, a hinge pin mounted axially in said casing and having an extension of non-cylindrical cross-section above said casing, a bushing for said hinge pin disposed near the open end of said casing and attached thereto, a thrust bearing for said hinge pin in said casing, a hub having a hinge-pin leaf attached thereto, said hub having a non-cylindrical axial hole adapted to non-rotatably engage said hinge pin extension but adapted to permit axial movement therein of said hinge extension, a coiled spring around said pin, one end of said spring being attached to said pin and the other end to said bushing, and means for adjusting the longitudinal position of said hub on said shaft extension.

2. A load-bearing closer hinge comprising a hollow cylindrical casing, a casing leaf attached by an edge to said hollow casing, a hinge pin mounted axially in said casing and having an extension of non-cylindrical cross-section above said casing, a thrust bearing for said hinge pin in said casing, a bushing for said hinge pin disposed near the open end of said casing and attached thereto, a hub having a hinge pin leaf attached thereto, said hub having a non-cylindrical axial hole adapted in its lower portion to

non-rotatably engage said hinge pin extension but adapted to permit axial movement therein of said hinge pin extension, a coiled spring around said pin, one end of said spring being attached to said pin and the other end to said bushing, and a threaded plug in the upper threaded plug in the upper threaded portion of said hole adapted to press upon the end of said extension, whereby to control the longitudinal position of said hub and its attached leaf, relative to said casing.

3. A load-bearing closer hinge comprising a hollow cylindrical casing, a casing leaf attached by an edge to said hollow casing, a hinge pin mounted axially in said casing and having an extension above said casing, a thrust bearing for said hinge pin in said casing, a hub having a hinge-pin leaf attached thereto, said hub having an axial hole adapted in its lower portion to engage said hinge pin extension and to permit axial movement therein of said hinge pin extension, a threaded plug in the upper threaded portion of said hole adapted to press upon the end of said extension, whereby to control the longitudinal position of said hub and its attached leaf relative to said casing, a rotatable bushing in the upper

end of said hollow casing around said hinge pin, said bushing having radial holes accessible from the periphery thereof, a coil spring around said hinge pin, one end being anchored to the hinge pin and the other to said bushing, and a removable stop pin adapted to be inserted in one of said radial holes in said bushing and to abut the edge of the casing leaf to hold said spring in tensioned condition.
